Term of patent 14 years

(Cl. D56—4)

FIG. 3

That side of the television receiver cabinet not shown in the drawings is identical to the corresponding side shown.

The back of the television receiver cabinet is unornamental.

The dominant features of the design reside in those portions shown by means of full lines in the drawings.

What is claimed is:

The ornamental design for a television receiver cabinet, substantially as shown and described.
